UNITED STATES PATENT OFFICE.

SIDNEY M. KNAPP, OF NEW YORK, N. Y.

DESIGN FOR A SUPPORT FOR A TELEPHONE-RECEIVER.

54,322.

Specification for Design.

Patented Dec. 23, 1919.

Application filed August 18, 1919. Serial No. 318,422. Term of patent 3½ years.

To all whom it may concern:

Be it known that I, SIDNEY M. KNAPP, a citizen of the United States, residing at the borough of Bronx, county of Bronx, city and State of New York, have invented a new, original, and ornamental Design for a Support for Telephone-receivers, of which the following is a specification, reference being had to the accompanying drawing, forming part thereof.

The figure is a perspective view of a support for telephone receivers, showing my new design.

I claim:

The ornamental design for a support for a telephone receiver, as shown.

SIDNEY M. KNAPP.
